UNITED STATES PATENT OFFICE.

HERMAN H. DOEHLER AND LOUIS H. MORIN, OF NEW YORK, N. Y., ASSIGNEES TO
DOEHLER DIE-CASTING CO., A CORPORATION OF NEW YORK.

SPOOL.

Application filed July 1, 1925. Serial No. 40,738.

Metallic die-cast spools have to a large extent replaced wooden spools for holding smaller sizes of wire such as is wound into electromagnetic coils, for example. These 5 spools have an axial bore of a suitable size to fit upon a spindle, while the outside diameter of the spools must be considerably larger in order that the first layers of the wire will not be wound so small as to make 10 the wire wavy and hard to rewind. For the sake of lightness and economy in metal, the metal spools are made in the form of relatively thin shells with an axial bearing tube mounted within them and concentrically 15 spaced from the spool body. The mounting of this axial tube presents a problem to which our invention is directed.

The metallic spools heretofore commonly used have an integral bearing for the tube 20 at one end, and at the other end a seat for a disc having a central hole forming a bearing for the opposite end of the tube. In this type of spool the tube is assembled in the spool after the spool body is cast, the 25 ends of the tube being expanded outside the two bearings to hold it against longitudinal movement, and the parts are suitably shaped to lock the tube to the spool body against relative angular movement. 30 The pulling of the core requires that one of the end bearings be removable.

In accordance with our invention the tube is permanently united to the spool body through a single integral web which may be 35 disposed anywhere within the spool and which so tightly embraces the tube as to hold it against any relative movement. Practically this is accomplished by casting the spool upon the tube as an insert. The 40 web may be made quite thin since it is subjected to relatively little strain and its embracing portion may be elongated to the extent necessary to effect the requisite rigidity. The embraced portion of the tube may 45 be knurled the better to secure the parts together, although it will be found that ordinarily this is unnecessary.

In the drawings we have shown two embodiments of our invention differing primarily in the location of the attaching web, Figures 1 and 2 being, respectively, a longitudinal section and a left end view of one form, and Figures 3 and 4 being corresponding views of another form.

In the form of spool shown in Figures 1 55 and 2, the attaching web is at the extreme end of the spool. The body 1 is a relatively thin shelled tube of die-cast metal having the usual flanged ends 2 and 3. The axial bearing tube 4 is composed of suitable hard 60 metal, such as steel, and is shown as somewhat shorter than the over-all length of the spool. This tube 4 is materially smaller 65 than the shell 1, and consequently there is a considerable annular space 5 between the tube and the shell. A web 6, which is integral with the shell 1, couples the tube and shell, this being accomplished, as above suggested, by casting the spool directly upon the tube. In the construction of Figures 1 70 and 2, this web 6 is, as above stated, at the extreme end of the shell 1, and a corresponding end of the tube 4 has its external surface knurled, while the embracing portion of the web is somewhat elongated. 75 Due to the different co-efficients of expansion and contraction possessed by the metals of the shell and of the tube, the web embraces the tube very tightly when the casting is cooled and forms a rigid connection 80 between the two parts. The opposite end of the casting is left open for core-pulling purpose. A small hole 7 may be provided in the web 6 for the reception of a driving pin. 85

We have found that the axial tube is ordinarily held sufficiently rigidly for all practical purposes when the web is located at the extreme end, as in the construction of Figures 1 and 2. However, if preferred, 90 the web may be centrally disposed, as shown in Figures 3 and 4. In this form, the web 6^a has its embracing portion extended as far as may be necessary toward the opposite ends of the tube, and the tube is knurled at 95 the center, which is the part that is embraced. This type of coupling might be preferable where the spool is quite long. The cores are pulled from each end of the casting and, in this instance, the shell is 100 thickened or provided with a longitudinal boss at one point to accommodate the driving hole 7.

It is obvious that various modifications may be made in the construction shown in 105 the drawings and above particularly described and illustrated within the principle and scope of our invention.

We claim:

1. A metallic hollow spool including an axial tube of metal harder than the spool body and of substantially smaller diameter than the hollow interior of the spool, and an integral, transverse tube-gripping portion within the spool fitting around the tube for a small part of the tube's length with sufficient tightness to hold the tube positively against relative longitudinal or angular movement.
2. A hollow spool of die-casting metal

with an axial tube of harder metal substantially smaller in diameter than the hollow interior of the spool and having an external 15 roughened portion, and an integral web within the spool gripping the tube about the roughened portion sufficiently tightly to prevent relative longitudinal or angular movement.

In witness whereof, we hereunto subscribe our signatures.
